UNITED STATES PATENT OFFICE

JOHN L. CARD, OF BALTIMORE, MARYLAND, ASSIGNOR TO UNITED STATES HOFFMAN MACHINERY CORPORATION, OF NEW YORK, N. Y., A CORPORATION OF DELAWARE

GARMENT PRESS

Application filed May 28, 1929. Serial No. 366,693.

This invention relates to garment presses and more particularly to presses wherein power means are employed to effect a final heavy pressure after the press head has been 5 brought into preliminary pressing position by hand. In presses of this type there is a decided danger that the operator may have his hands or fingers between the cooperating press elements when the power mechanism is 10 actuated, and it is therefore desirable that means be provided to prevent actuation of the power mechanism except when the press elements are in pressing relation, which condition is, of course, dependent on the withdrawal of the hands.

It is an object of the present invention to provide a clutch or interconnection between the power mechanism and the press head, means being associated with the clutch to 20 prevent clutching action except when the press head has been lowered to contact the goods on the lower press element or buck.

It is also an object of the invention so to construct the clutch that it is automatically 25 disengaged when maximum power is applied, the application of power being maintained as long as desired. The clutch parts may then be reengaged to return the press head to normal position. The clutch per se 30 is the subject matter of copending application Serial Number 365,404, filed May 23, 1929, by John L. Card.

Reference to the following description and the appended drawings will enable a clear 35 understanding of the invention to be had:

Figure 1 is a side elevation, partly in section, of a garment press showing the relation of the clutch mechanism to the press when the latter is open;

Fig. 2 is a view similar to Fig. 1 except that the press is closed and the clutch is in position to permit application of power;

Fig. 3 is a front elevation, partly in section, taken on line 3—3 of Fig. 5;

Fig. 4 is a top sectional view taken on line 4—4 of Fig. 3;

Fig. 5 is a side sectional view taken on line 5—5 of Fig. 3; and

Fig. 6 is a perspective view of the clutch,

the parts being separated for clearness of illustration.

Referring to the drawings, the garment press illustrated is of that type in which a movable press head 11 is adapted to be swung downwardly into pressing relation with a fixed press element or buck 12. The head 11 is fixed to a lever 13 fulcrumed intermediate its ends, as at 14, to a press frame 15. Toggle mechanism comprising the links 16, 17, is employed for exerting pressure on the lever, a connecting rod 18 being associated with the power mechanism for this purpose. Springs 19, only one of which is shown, connect the lever 13 with the press frame and tend to 60 maintain the lever in raised or open position. The above described parts are of the usual construction and relation and their details require no further explanation.

The power mechanism and the clutch for 70 connecting the toggle thereto are illustrated in detail in Figs. 3 and 4. A driving shaft 21, connected to and continuously rotated by a motor 22, is provided near one end with a worm 23 meshing with worm gear 24. Coaxially aligned with the worm gear, but rotatable with respect thereto, is a driven shaft 25 having a crank portion 25'. Shaft 25 is journaled in a boss 26 on the housing 27 and has a reduced portion 28 fitting within a sleeve 29. 80 The sleeve likewise has a reduced portion 31 journaled in a boss 32 in the housing cover 33. The worm gear 24 and sleeve 29 are fixed with respect to each other, a key or other suitable fastening means 30 holding the worm 85 gear to the sleeve. It is to be noted that shaft 25 and sleeve 29 mutually support each other, thus dispensing with intermediate bearings, but the sleeve is free to rotate on the shaft.

One end of sleeve 29 is enlarged and milled 90 to provide a number of ratchet teeth 34 adapted to cooperate with a pawl member 35 on plate 36. This plate has a hub portion 36' which is keyed to shaft 25, so that when the pawl 35 engages the teeth 34 on the sleeve 95 29, the shaft 25 rotates with worm gear 24. The pawl is fastened intermediate its ends to a pin 37 rotatably supported in place 36 and in the segmental member 38 fastened to the plate, the pawl being supported between 100

the plate and segment to minimize the danger of shearing the pin when the clutch is thrown in. Spring 39, fastened at one end to plate 36 and at its other end to a disk 40 secured to pin 37 and bearing against an annular flange 41 on the plate 36, normally tends to rotate the pawl to engaging position with respect to ratchet teeth 24. Mounted in a forked end portion 42 of the pawl is a cam follower 43 which rides on the inner periphery of an annular cam ring 44, which, as illustrated best in Fig. 6, has two spaced high surfaces $a-b$, $c-d$, and a corresponding number of low portions or "valleys" $b-c$, $d-a$, designed to raise or lower the engaging end of the pawl with respect to the teeth 34. The outer periphery 45 of the ring is concentric with the shaft 15 and is mounted in the housing 27 to provide a sliding fit therein. Lateral displacement of the ring is prevented by an annular flange 46 on the housing and segments 47 removably secured to the housing by screws 48. The cam ring is shiftable circumferentially with respect to the housing, the means for shifting the ring comprising a forked rocker arm 49 cooperating with pin 51 on the ring. The rocker shaft 52 is journaled in the housing, as shown in Fig. 5, and has secured to the projecting end thereof a second arm 53 connected by links 54 with a hand lever 55, the latter being within reach of the operator. Normally the arm 49 is held in the position shown in Fig. 3 by a spring 56 surrounding shaft 52 and secured to the shaft and housing respectively. A recess 57 at the lower portion of the cam ring provides stop shoulders 58, 58' which cooperate with an abutment 59 on the housing, thereby limiting the circumferential sliding movement of the cam ring.

The operation of the press will be apparent if it is first assumed that the press is open as shown in Fig. 1. It will be noted that in this position the cam follower 43 corresponds with the point a on the shiftable cam ring (see Fig. 6). Since the pawl is secured to the plate 36, which in turn is keyed to shaft 25, it will be moved to the position indicated in Fig. 2 when the press head is lowered by hand to preliminary pressing position, the shaft 25 being rotated due to its connection with toggle link 17. The roller 43 does not, however, reach the point b on the cam and cannot, therefore, permit the pawl to rock into engagement with teeth 34. To throw the pawl into engaging relation with the teeth it is necessary to shift the cam ring until the recess or valley $b-c$ underlies the cam follower and this is done by depressing lever 55 to rock the shifting fork 49 to the position indicated by dotted lines in Fig. 3. It is to be understood that shifting of the ring alone will not throw the pawl into engagement with the teeth 34, it being first necessary to position pawl 35 with reference to the point

b of the cam, the distance between the roller and point b when the press is preliminarily closed being slightly less than the distance through which the cam may be shifted.

When the roller drops into the depression $b-c$, the pawl engages the teeth 34 and the driving and driven shafts are coupled so that the crank arm 25' is rotated to bring the connecting rod 18 to a horizontal position, at which time the toggle is straightened and maximum pressure applied. It is apparent that crank 25' and arm 18 are in alignment in this latter position, that is the crank is on dead center. Since the spring 56 tends to turn the cam ring in a counter-clockwise direction, the ring tends to follow the roller 43. The shoulder 58 on the ring limits the return movement of the cam, however, and brings the ring to rest in a position at which the cam surface $c-d$ will engage the roller 43 simultaneously with the application of maximum pressure, that is, when the crank 25' is on dead center. Pawl 35 is therefore disengaged during the application of maximum pressure.

When it is desired to break the toggle the cam ring is again shifted by depressing lever 55. The high portion $c-d$ of the cam is substantially the length of the shifting movement of the ring and as the ring is shifted in a clockwise direction roller 43 will drop into the depression $d-a$. This latter depression is sufficiently long to permit engagement of the pawl and teeth until the press is fully open when the pawl will again be disengaged by coaction of the follower and cam surface $a-b$. The above described cycle is repeated for each pressing operation.

It is obvious that the actuation of the clutch is dependent on the preliminary closing of the press and that there is no danger of the power being applied while the operator's hands are between the pressing elements. It is likewise obvious that maximum pressure may be applied for any desired period and that the clutch is easily controlled by the operator. While the mechanism illustrated is simple of construction and a preferred form of the invention, it is susceptible of modification and may be changed to meet the requirements of the service imposed upon it.

What is claimed is:

1. In a garment press, the combination of a fixed pressing element; a movable element adapted to be moved into pressing relation with said fixed element by the operator; constantly operated power means; crank means connected to said movable element for applying pressure thereto; clutch means for connecting said power means to said pressure applying means, said clutch means being connected to said crank means and rotatable therewith; means constantly urging said clutch means towards engaging position; 130

means normally holding said clutch means in disconnected position; and operator operated means for shifting said holding means to permit said urging means to effect actuation of said clutch means only when said elements are in pressing relation to apply heavy pressure and upon a subsequent operation of the operator operated means to open the press.

10 2. In a garment press, the combination of a fixed pressing element; a movable element adapted to be moved into pressing relation with said fixed element by the operator; constantly operated power means; means connected to said movable element for applying pressure thereto; a pawl on said pressure applying means; a toothed member on the power means and adapted to engage said pawl; means constantly urging said pawl 20 into engagement with said toothed member; shiftable cam means for holding said pawl out of engagement with said toothed member during a predetermined movement of said movable element; and means for shifting said cam; said pawl and toothed member engaging each other only after said predetermined movement of the movable pressing element and shifting of the cam to apply heavy pressure, being disengaged during application of 30 heavy pressure, and thereafter being reengaged by a subsequent shifting of the cam means to open the press.

3. In a garment press, the combination of a fixed pressing element; a movable element 35 adapted to be moved into pressing relation with said fixed element by the operator; constantly operated power means; means connected to said movable element for applying pressure thereto; a pawl on said pressure applying means; a toothed member on said power means and adapted to engage said pawl; means constantly urging said pawl towards engaging position; a shiftable ring; means on said ring for holding said pawl 45 out of engagement with said toothed member during a predetermined movement of said movable pressing element; means for shifting said ring; means on said ring for disengaging the pawl from the toothed member 50 after a predetermined engagement thereof; and other means on said ring to permit said urging means to effect engagement of the pawl and toothed member for opening the press when said cam is again shifted.

55 4. In a garment press, the combination of a fixed pressing element; a movable element adapted to be moved into pressing relation with said fixed element by the operator; constantly operated power means; means connected to said movable element for applying pressure thereto; a pawl on said pressure applying means; a toothed member on said power means and adapted to engage said pawl; means constantly urging said pawl 60 towards engaging position; a shiftable ring,

said ring having two spaced cam surfaces thereon to hold the pawl out of engagement with the toothed member, one of said surfaces engaging the pawl when the press is being moved from fully open to substantially closed position, the other of said surfaces engaging the pawl during maximum pressure application, the pawl being engageable with the toothed member when overlying one of the spaces between said surfaces to effect heavy pressure, and engageable with the toothed member when overlying the other space between the surfaces to open the press; and means for shifting the ring to permit engagement of the pawl and toothed member.

In testimony whereof I have signed my name to this specification.

JOHN L. CARD.
